Joseph Vietze
James O. Hamilton
Attorney

UNITED STATES PATENT OFFICE.

JOSEPH VIETZE, OF HYDE PARK, MASSACHUSETTS.

JACQUARD LOOM.

Application filed June 2, 1923, Serial No. 642,997.

To all whom it may concern:

Be it known that I, JOSEPH VIETZE, a citizen of the United States, and a resident of Hyde Park, in the county of Suffolk and 5 State of Massachusetts, have invented certain new and useful Improvements in Jacquard Looms, of which the following is a full, clear, concise, and exact description.

My present invention relates to looms, and 10 more particularly to a safety device for looms of the Jacquard type.

In prior Jacquard machines utilizing the ordinary griff, there was a tendency on the part of the hook to swing under the blades 15 of the griff as the griff descended. Various expediencies were designed to overcome this fault, such as deepening the blades of the griff, providing auxiliary griff blades, and the like. None of these was satisfactory, however, as the use of deep blades made it difficult to replace broken hooks while with the use of auxiliary griff blades, the hook had a tendency to swing back 20 under the auxiliary blade because of the great length of the hook, and particularly when the loom was run at a high speed. Another serious defect in prior machines was due to the complete derangement of the 25 hooks and their associated needles because of the frequent breaking of the pin connecting the connecting rod with the grate operating lever and when this contingency happened, the entire grate bar fell to such a distance that the lower end of the hooks resting on 30 the bars of the grate no longer supported the upper end of the hooks in operative relation with the griff blades and consequently when the hook was lowered, the upper end thereof swung under the griff blade and necessitated frequent adjustment and 35 replacement of parts.

In my present invention I have overcome 40 defects of prior apparatus of this type and have associated with the Jacquard loom an 45 adjustable stop bar which is associated with the grate in such a manner as to limit the downward movement thereof and prevents, in this manner, such grate, with its associated grate bars, from ever falling or dropping 50 to such a level as to allow the upper end of the hooks to become deranged with respect to the griff blades. Regardless of whether or not, therefore, the pin connecting the connecting rod with the grate operating 55 lever breaks, there is no possibility, in my improved device, of any damage resulting

to the loom or any of its parts from this cause.

The object of my invention, therefore, is an improved safety device for looms of the 60 Jacquard type, insuring the safety of vertically arranged hooks.

In the accompanying drawings illustrating the preferred embodiment of my invention, 65

Fig. 1 is a side elevation;

Fig. 2 is a fragmentary sectional elevation on the line 2—2 of Fig. 1;

Fig. 3 is a perspective diagram illustrating the relation of my improved safety device to the grate and associated elements, 70 and

Fig. 4 is a perspective view of my improved safety bar.

Referring to the drawings, 10 designates a 75 base plate of the machine having mounted thereon a framework 11 and within the limits of which is located the operating mechanism of the loom. Arranged within the framework 11 and on one side thereof is a 80 needle plate or board 12 through which extends a plurality of parallelly arranged needles 13 in the usual manner, and these needles may extend through a pattern plate 14 on the same side of the machine and into a 85 spring box 15 on the opposite side, as is usual in machines of this character. Each of the needles 13 is provided with a hook portion 16 associated with a vertically mounted hook 17, the top end of which is 90 adapted to be ordinarily engaged by a griff blade 18 constituting one element of a griff, such griff being comprised of a plurality of parallelly arranged blades 18 secured to a cross bar 19 which, in turn, has pivotally 95 mounted thereto at its upper end a connecting rod 20 associated with an operating lever 21 operated in the usual manner and by means of which the griff is operated. The upper portion of the hook 17 normally 100 hooked over the griff blades 18, while the hook 22 on each of the hooks 17 is adapted to be engaged by one or the other of the grate bars 23 as the hooks are moved vertically by the griff. These grate bars are 105 arranged below and parallel to the griff blades 18 and have their ends secured in a grate frame 24 which is arranged for vertical sliding movement in the frame 11, a connecting rod 25 pivotally attached to the grate frame 110 24 having its lower end pivotally connected to a grate operating lever 26, both the grate

operating lever and the griff operating lever being pivotally mounted intermediate their ends in a suitable bearing in a boss 27 formed integral with, or secured to, the top 5 of the base 10. To the outer free end of the grate operating lever 26 is pivotally connected the upper end of a connecting member 28 by a pin 29.

The ends of the needles, extending 10 through the needle plate or board 12, encounter the pattern plate 14 of the device and certain predetermined ones of the needles 13 have the hook portion 16 thereof brought firmly against their associated hooks 17 and, 15 on the next upward movement of the grate 24, such predetermined hooks 17 are lifted off the griff blades 18 and forced laterally with respect thereto, so that, on the next downward movement of the grate 24, such 20 upper ends of the hooks 17 fail to register with the griff blades 18 and therefore fall below the upper edge of such griff blades. If the downward movement of the grate frame 24 is too great, the upper end of the hook 25 17 may swing inward into such a position as to engage with the bottom edge of the griff blade 18 and, on the next upward movement of the grate frame 24, such hook will be jammed against the lower edge of the 30 griff blade and buckled, thereby throwing the entire apparatus out of adjustment and necessitating renewal of the hook and readjustment of the parts. The pin 29 is frequently broken because of the rapid movement and jarring of the entire machine, in which case the grate frame 24 drops downwardly below its normal level and throwing the entire set of vertically arranged hooks 17 out of adjustment and necessitating the 35 entire resetting of the machine. To obviate this defect, I have arranged a safety bar 30 provided on its ends with downwardly and rearwardly extending enlargements 31 each provided with a vertically arranged slot 32 40 adapted to register with slots 33 in the framework 11 and through which, and the slots 32, extend bolts 34 and by means of which the bar 30 may be adjusted vertically

with respect to the framework 11. On the upper face of the bar 30 formed integral 50 therewith and extending parallel thereto is a ledge 35 which is adapted to engage with a face 36 on the lower edge of the front of the grate frame 24. The bar 30 is set by means of the adjusting screws or bolts 34 55 with relation to the grate frame 24 so that, in the extreme downward permissible limit of the grate frame 24, the face 36 is engaged by the ledge 35. The device may now be operated in the usual manner, but, regardless of whether or not the pin 29 breaks or whether or not the griff blade employed is short or long, there is no danger of the upper end of the hooks 17 being engaged and damaged by the griff blades. 65

While I have necessarily shown and described the preferred embodiment of my invention somewhat in detail, it is to be understood that I may vary the size, shape, and arrangement of parts within wide limits 70 without departing from the spirit of the invention.

Having thus described my invention, what I claim as new is:

1. In a device of the kind described, the 75 combination of a frame, a grate frame mounted for reciprocation in a vertical plane in said framework, and a safety bar adjustably mounted in the framework and adapted to be engaged by, and limit, the 80 downward movement of the grate frame.

2. In a device of the kind described, the combination of a griff blade, a grate bar, means for moving said griff blade and grate bar in a vertical plane and independently 85 of each other, a hook carried by the grate bar and adapted to engage with the griff blade, means for moving said hook laterally of the griff blade at predetermined times, and means cooperating with the grate bar 90 for preventing injury to the hook when the upper end of such hook is disengaged from the griff blade.

In witness whereof I hereunto subscribe my name this 21 day of April, 1923.

JOSEPH VIETZE.
